UNITED STATES PATENT OFFICE.

MOSES OFFENBERG, OF BERLIN, GERMANY.

APPARATUS FOR REGULATING THE GAS-PRESSURE IN BURNERS.

SPECIFICATION forming part of Letters Patent No. 724,035, dated March 31, 1903.

Application filed December 11, 1901. Serial No. 85,538. (No model.)

To all whom it may concern:

Be it known that I, MOSES OFFENBERG, a subject of the King of Prussia, German Emperor, and a resident of 35 Luisen Ufer, Berlin, Kingdom of Prussia, German Empire, have invented a new and useful Apparatus for Regulating the Gas-Pressure in Burners, of which the following is an exact specification.

10 My invention relates to a new and improved apparatus to be attached to a gas-burner, which apparatus serves for regulating the gas-pressure.

In order to make my invention more clear, 15 I refer to the accompanying drawings, in which—

Figure 1 is a perspective view of my new apparatus. Fig. 2 is a vertical section of the same. Fig. 3 is a vertical section of part of 20 the same.

The apparatus consists of two nipples A and B, screwed together at C. Inside the nipple B a thread D is provided for screwing the same upon the gas-pipe. Within this nipple B a wire webbing a is provided, which 25 serves for diminishing the streaming velocity of the gas. Upon the upper edge of the nipple B a funnel-shaped cup b, preferably manufactured of aluminium, is arranged, in which 30 cup a metal ball c (preferably a steel ball) is situated. By using an aluminium cup and steel ball the rusting of the steel ball, which easily occurs in case an iron or other metal cup is used, is avoided. In the bottom of the cup

b a hole is provided, which is closed by the 35 metal ball c, whereby a regulation of the gas-pressure is attained. In the upper nipple A a second wire webbing d is provided, which serves for uniformly propagating the gas in the upper part of the nipple. This upper part 40 is provided with outside threads for screwing the burner upon the same.

In order to be able to use the apparatus itself as a burner, a cup e may be provided, which can be screwed upon the upper part of 45 the nipple A and which is provided with one or several holes f, through which the gas streams out.

Having thus fully described the nature of this invention, what I desire to secure by Letters Patent of the United States is— 50

In an apparatus for regulating the gas-pressure, the combination of two nipples screwed one upon the other, a cup provided with a hole in the bottom and situated upon the upper edge of the lower nipple, and a metal ball situated within the cup, with a wire webbing situated in the lower nipple below the cup and a second wire webbing situated in the upper nipple above the cup, substantially as described and for the purpose set forth. 55

In testimony whereof I have signed my name to this specification in the presence of two subscribing witnesses.

MOSES OFFENBERG.
